(57) **CLAIM**

We claim the ornamental design for a display screen or portion thereof with graphical user interface, as shown and described.

DESCRIPTION

The sole FIGURE is a front view of a display screen or portion thereof with graphical user interface showing our new design.

The outermost broken line showing of the display screen is for environmental purposes only and forms no part of the claimed design.

The broken lines in the FIGURE depict environmental subject matter and form no part of the claimed design.
